UNITED STATES PATENT OFFICE.

ANDREW W. GREEN, OF TORONTO, ONTARIO, CANADA.

FLOOR-FINISHING APPARATUS.

1,401,400.

Specification of Letters Patent. Patented Dec. 27, 1921.

Application filed December 15, 1920. Serial No. 431,019.

To all whom it may concern:

Be it known that I, ANDREW W. GREEN, of the city of Toronto, in the county of York, Province of Ontario, Canada, a subject of the King of Great Britain, have invented certain new and useful Improvements in Floor-Finishing Apparatus, of which the following is a specification.

This invention relates to floor finishing apparatus particularly adapted for use in polishing hardwood floors, and the like, and my object is to devise means to mechanically wax and polish the floor and reduce the amount of manual labor to a minimum.

15 A still further object is to devise a floor finishing apparatus which will be easy to operate and of good appearance. Further objects I have in mind will hereinafter appear.

20 I attain my objects by means of the constructions hereinafter described and illustrated in the drawings in which—

Figure 1 is a side elevation, partly in section, of the apparatus;

25 Fig. 2 a horizontal section taken in a plane above the carriage;

Fig. 3 a vertical section of the floor finishing tool with the polishing means attached;

30 Fig. 4 a side elevation of the brush attachment;

Fig. 5 a vertical section of the floor finishing tool with the wax carrying pad attached to the floating pad;

35 Figs. 6 and 7 side elevations of the apparatus having two different floor finishing tools attached; and

Fig. 8 a detail in plan of the handle supporting member.

40 In the drawings like numerals of reference indicate corresponding parts in the different figures.

1 is a carriage comprising a frame 2 provided with wheels or suitable gliders 3. The 45 carriage is also provided with a furniture protector 4 and a handle 5. To the frame 2 is suitably secured a motor 6 adapted to be connected to a source of electric supply.

A floor finishing tool 7 suitably mounted 50 on the frame 2 is adapted to be rotated by the motor 6. The finishing tool 7 includes a frame 8 and to the underside of this frame I apply a resilient cushion 9. Polishing means 10 are provided under- 55 lying the cushion 9 and preferably secured

to the frame 8 by a strap 11 fastened around the periphery of the frame by a clamp 12.

The resilient cushion 9 is preferably formed of felt pads 13 and upholstering filling 14. A cork buffer pad 15 is preferably used intermediate the frame 8 and the upper pad 13.

I prefer to rotate the floor finishing tool 7 by the motor 6 in the following manner: The motor is provided with a depending 65 spindle 16 which as usual is held from longitudinal movement in its bearings and the frame 8 is provided with a bored hub 17 which is adapted to be sleeved on the end of the spindle 16. A grub screw is 70 provided in the hub and adapted to form a driving connection with the spindle. From this arrangement it follows that as much of the weight of the motor and frame 75 may be applied to the brush as experience dictates to secure the best results and further adjustment may be made as wear of the bristles takes place. This arrangement permits the finishing tool 7 to be vertically adjusted on the spindle. To allow the frame 80 8 and the pad carried thereby to "float" relative to the floor and spindle 16, the latter is provided with a keyway 27 which engages the grub screw to rotate the frame and the pad. Of course, the frame 2 is provided 85 with a hole to provide clearance for the hub and spindle.

A felt collar 18 is preferably secured to the upper side of the frame 2 and to this collar is secured the motor 6. This construction permits a longer hub 17 to be used, thus making the finishing tool steadier when rotated and also cushions the motor.

I prefer to form a groove 19 in the periphery of the frame 8 to prevent the strap 11 95 slipping off the frame.

To wax the floor I provide a wax carrying attachment 20 having perforations 21 and adapted to be secured to the floating frame 8. A porous member 22 underlying the attachment 20 is adapted to spread the wax evenly on the floor. It will readily be seen that by removing the polishing means 10 and securing the attachment 20 and the porous member 22 to the frame 8 100 105 that the apparatus will be converted to a floor waxer.

The resilient cushion 9 is used to apply pressure to the wax which has been spread on the upper side of the pad attachment 110

20, thus squeezing the wax through the perforations 21. I prefer when waxing to remove the filling 14 from the cushion 9 and use the pads 13 which present a firmer 5 pressing surface to the wax. Of course, a thin unpenetrable disk may be inserted between the lower pad 13 and the wax to keep the lower pad free of wax.

After the floor is waxed I prefer to brush 10 it. For this purpose I may provide a frame 23 provided with a brush 24. The frame 23 is provided with a hub 17 having a grub screw adapted to form a driving connection with the spindle 16 of the motor.

15 It will readily be seen that the surface of the floor may be smoothed before waxing by securing sand paper to the under side of the finishing tool 7.

For finishing floors I prefer to mount a 20 plurality of finishing tools on the frame 2, each finishing tool adapted to perform a different operation at the same time thus reducing the amount of time taken to finish the floor and also the manual labor required.

25 Of course the different tools are mounted so that the different operations may be performed in their correct order.

I provide a stub spindle 25 which is journaled on the frame 2 in any suitable manner to allow it to move lengthwise. This 30 stub spindle is adapted to carry any type of floor finishing tool hereinbefore described and is also adapted to be rotated by the motor 6 in any suitable manner. This arrangement permits the spindle 25, the frame 8 and the pad carried by the frame to "float" 35 relative to the floor.

Preferably the stub spindle 25 is rotated by securing a grooved pulley to it and also 40 securing a grooved pulley to the spindle 16. An endless belt is carried by these pulleys to transmit power to the stub spindle 25.

In Fig. 6 I show the stub spindle 25 carrying the frame 8 provided with the waxing 45 attachment 20 and the motor spindle 16 carrying the frame 23 provided with the brush 24. Fig. 7 shows the apparatus reversed and the floor finishing tool 7 substituted for the waxing attachment 20.

50 It is evident that other combinations of tools might be employed to give satisfactory results.

A modification of the handle supporting means is shown in Fig. 7 to allow the handle 55 to swing to any desired angle in a horizontal plane. On the carriage 1 is secured a supporting member 28 in which is vertically journaled an upwardly extending pin 29. The handle 5 is provided with a slotted head 60 30 adapted to receive the upper end of the pin 29 and a horizontal pin 31 transversely journaled in the pin 29 forms a horizontal pivotal connection for the handle. It is evident that with this arrangement the handle 65 35 may be swung vertically on the horizontal

pin 31 and swung in a horizontal plane by means of the vertical pin 30. To lock the handle at any desired angle in a horizontal plane the supporting member 28 is provided with holes arranged concentrically with the vertical pin 30, the holes being adapted to receive a depending projection 32 carried by the handle. To change the position of the handle relative to the carriage the handle is first swung upwardly to disengage the 75 projection 32, then swung horizontally to the desired position and then lowered to permit the projection to engage the hole.

To prevent dust rising when the device is in use the carriage 1 is provided with depending sides and ends to substantially inclose the finishing tools. One of the depending sides is provided with a hinged door 33 so that the finishing tools may be easily removed or attached to the spindles.

80 The construction of this machine is such that the spindle 16 may be an extension of the spindle of the motor of a vacuum cleaner, so that the expense of the machine to any one already possessing a vacuum cleaner is 90 considerably reduced.

If a floor is to be treated with a cleaning fluid, a sponge saturated with the fluid may be placed beneath the pad 13 on the floating frame 8, and held in position by the outer 95 covering and the device run over the floor.

In the operation of this machine I prefer to depend on speed rather than pressure, both in the application of the wax and in polishing. The machine may thus be made 100 light in weight and small in size, thus rendering it particularly adapted for household use and further may be cheaply manufactured.

The mode of operation of the double form 105 of the machine is substantially as follows.

The brush is directly connected to the motor spindle and the waxing attachment to the floating pad. The handle is then adjusted so that the waxing attachment leads 110 and the brush follows, thus effectively distributing the wax applied by the waxing attachment.

After waxing the waxing attachment is removed and the polishing covering 10 applied to the pad on the floating frame 8. The handle is then adjusted so that the polishing means follows the brush and the floor again gone over with the apparatus. The floating of the frame, either when carrying the waxing attachment, the polishing covering or the cleaning attachment is of 120 very great importance as the pressure of the tool on the floor remains constant and the work is always properly performed despite any unevenness of the floor and with a minimum of wear on the tools. It also follows from the construction described that as much pressure as may be necessary is 125 readily applied to the brush by adjusting 130

it longitudinally on the spindle 16 as hereinbefore described.

The fact that the handle may be adjusted to any horizontal angle enables the operator 5 to work into awkward corners and other places where a device with merely an ordinary bent handle could not operate and thus entirely obviates the necessity for hand work.

10 What I claim as my invention is:

1. A rotatable floor finishing tool comprising a frame; a resilient cushion adjacent the lower side of said frame; a perforate wax carrying pad secured below the cushion; 15 a porous member secured under the carrying pad and adapted to spread the wax.

2. In floor finishing apparatus the combination of a carriage adapted to engage the floor; a motor secured to said carriage and 20 provided with a depending spindle; a brush carried directly on the spindle and vertically adjustable thereon; and a floating pad journaled on said carriage and adapted to be rotated by said motor to yieldingly engage 25 the floor.

3. In floor finishing apparatus the combination of a carriage provided with floor finishing means; a supporting member secured to said carriage and provided with 30 holes; a pin vertically journaled in said supporting member; a handle horizontally journaled on said pin so that the handle may swing horizontally and vertically; and a depending projection carried on the handle 35 adapted to engage one of the holes.

4. In floor finishing apparatus, the combination of a carriage adapted to engage

the floor; a motor secured to the carriage and provided with a depending spindle; a brush carried directly on the spindle; 40 means for causing as much of the weight of the carriage and motor as desired to be applied to the brush; and a floating pad journaled on the carriage and adapted to be rotated by the motor to yieldingly engage 45 the floor.

5. In floor finishing apparatus, the combination of a carriage provided with a bearing; a motor secured to the carriage and provided with a depending spindle; a floor 50 finishing tool carried directly on the spindle; a second spindle journaled in the bearing and axially movable therein and adapted to be rotated by the motor; and a frame secured to the last mentioned spindle and 55 adapted to carry a floor finishing tool.

6. In floor finishing apparatus, the combination of a carriage provided with a bearing; a motor secured to the carriage and provided with a depending spindle; a floor 60 finishing tool carried directly on the spindle; a second spindle journaled in the bearing and axially movable therein; a floor finishing tool secured to the last mentioned spindle; a pulley secured to the spindle of 65 the motor; a pulley secured to the second spindle; and a belt carried by the pulleys.

Signed at Toronto this 11th day of December, 1920, in the presence of the two undersigned witnesses.

ANDREW W. GREEN.
